SPORTSMAN'S COAT

Frank H. Mahoney, Burlington, Vt., assignor of
one-half to William Knox, Burlington, Vt.

Application April 11, 1936, Serial No. 73,913

2 Claims. (Cl. 2-94)

This invention relates to an improved sportsman's coat of the Norfolk type.

It is the purpose and object of the invention to provide an improved sportsman's coat that possesses the capacity of being quickly modified to present a normal appearance acceptable for street wear.

In a more specific aspect it is the purpose and object of the invention to provide a sportsman's coat having a detachable pack-containing bag that may readily be secured to the coat through means normally concealed from view.

It is a further object of the invention to provide a sportsman's coat that can be utilized both for sports wear and street wear and which can be transformed with a minimum of effort and without in any way impairing the normal appearance of the coat.

It is likewise an object of the invention to provide a coat that can be economically manufactured and one that will give satisfactory service in use.

Coming now to a specific description of the invention, like reference characters in the drawings refer to like parts.

Figure 1 is a rear elevation of the sportsman's coat having the pack-containing bag in position thereon;

Figure 2 is a detailed perspective of the pack-containing bag;

Figure 3 is a rear elevation of the coat with the pack-containing bag removed and parts shown in section;

Figure 4 is a sectional view taken along the line 4-4 of Figure 1;

Figure 5 is a sectional view taken along the line 5-5 of Figure 1;

Figure 6 is a rear elevational view of a modified form of sportsman's coat; and

Figure 7 is a detailed perspective view of the upper end of the pack-containing bag shown in Figure 6.

Referring to Figure 1, the sportsman's coat is indicated generally at 1 and is provided with the vertically spaced box plaits 2 and the belt 3. The box plaits 2 are of a sufficient width that they will completely overlie and conceal the complementary "zipper" fasteners 4 and 5 which cooperate to hold the pack-containing bag 6 in position on the coat.

The pack-containing bag 6 is provided at either side thereof with a complementary "zipper" fastener element 7 (see Figure 2), and in the modification of Figures 1 to 3, the top of the

pack-containing bag can be closed through the medium of the snap fasteners 8.

The pack-containing bag 6 is of such dimensions and so constructed that the "zipper" elements 7 carried thereby are spaced apart a distance equal to the spacing between the complementary "zipper" elements 4 and 5 carried by the coat. The arrangement is such that the pack container 6 may be readily affixed to or removed from the coat through the medium of the "zipper" fasteners merely by the operation of the "zipper" fastener clips 9. The bag 6 can thus be readily attached to or removed from the coat 1 and, when removed, the complementary "zipper" fastener elements 4 and 5 are completely concealed beneath the box plaits 2 so that, from all outward appearances, the coat is of conventional form and may be worn for conventional use.

It will be apparent that the pack-containing bag is located in the most advantageous position on the coat and that the box plaits 2 help to suspend the weight from the shoulders of the wearer. The pack-containing bag 6 can, of course, be removed from the coat either in packed or empty condition. This makes the coat exceedingly practical for hikers and for like uses since the pack may be immediately removed from the coat and laid aside without necessitating the wearer's laying aside of the garment.

It frequently happens with sports coats of this general type that the wearer is compelled, in order to gain access to the pack, to take off the coat and leave it off during the complete unpacking operation, which not infrequently results in exposure after exertion, at a time when the coat is most needed by the wearer. All of these objectionable factors are completely overcome through the use of the present invention.

In Figures 4 to 7 there is shown a modified form of coat in which the pack-containing bag designated 10 is suspended from the top of the back by a "zipper" element indicated generally at 11. In this modification one of the "zipper" elements 12 is carried by the back of the bag 10 whereas the other complementary "zipper" element is positioned underneath the plait 13 at the bottom of the yoke in the back of the coat. In this modification the top of the bag 10 is likewise closed through the medium of the snap fasteners indicated at 14. Also in this modification the box plaits may be eliminated from the coat. However, it is advantageous in some instances to provide both the top suspension as disclosed in Figures 4 to 7 and the side suspension as disclosed in Figures 1 to 3, and it is distinctly understood that

the disclosed invention embraces the idea of suspending the packing bag from the top through "zipper" fasteners, as specifically disclosed in Figure 6, and also through the sides, as specifically disclosed in Figure 1. The latter arrangement provides a double suspension and enables the coat to be used for the carrying of heavy packs.

From the foregoing it will be apparent that, in accordance with the present invention, there is provided an attractive sportsman's coat that can be produced along conventional style lines without necessitating the provision of cumbersome fixed pockets, packed bags, and the like. It is further apparent that the coat may be produced from all suitable fabrics and that it is a most economical garment for the reason that it is adapted not only to sports wear but to conventional use. It is notoriously true that the usual sports coat is relegated to disuse most of the time, whereas a garment constructed in accordance with the present invention may serve the wearer under a large variety of conditions.

Having thus described my invention, what I claim is:

1. A coat having a pair of vertically spaced plaits on the back, "zipper" elements affixed to the coat beneath the adjacent edges of said plaits and concealed thereby, a pack-receiving bag carrying parallel disposed "zipper" elements spaced apart the same distance as the "zipper" elements carried by the coat, and means for effecting union of the complementary "zipper" elements on the coat and bag.

2. An improved coat comprising spaced apart vertical plaits on the back thereof extending over the shoulders and having opposed free marginal edges, complementary "zipper" elements secured to the coat beneath said opposed marginal edges in such relation thereto as to be normally concealed thereby, and a pack-containing bag carrying parallel disposed "zipper" elements spaced apart the same distance as the "zipper" elements affixed to the coat and arranged and constructed to be detachably secured to said coat whereby the points of attachment of the bag to the coat lie in the vertical lines of said plaits.

FRANK H. MAHONEY.
